UNITED STATES PATENT OFFICE

149,159

DESIGN FOR AN APPLICATOR OR SIMILAR
ARTICLE FOR BEAUTY AND HEALTH
TREATMENTS

Dolletta M. Ackerman, Los Angeles, Calif.

Application June 29, 1946, Serial No. 131,177

Term of patent 14 years

(Cl. D83—1)

To all whom it may concern:

Be it known that I, Dolletta M. Ackerman, a citizen of the United States, residing in Los Angeles, in the county of Los Angeles, State of California, have invented a new, original, and ornamental Design for an Applicator or Similar Article for Beauty and Health Treatments, of which the following is a specification, reference being had to the accompanying drawing, forming a part thereof.

Figure 1 is a side elevational view of an applicator or similar article for beauty and health treatments showing my new design.

I claim:

The ornamental design for an applicator or similar article for beauty and health treatments, as shown.

DOLLETTA M. ACKERMAN.
